United States Patent Office

Des. 201,201
Patented May 25, 1965

201,201

UNIVERSAL JOINT TESTER

Allen C. Wideburg, Chicago, Ill., assignor, by mesne assignments, to Avrum Gray and Sheldon W. Gray, both of Chicago, Ill.

Filed Feb. 10, 1964, Ser. No. 78,565

Term of patent 14 years

(Cl. D52—6)

FIG. 2

Des. 201,201

PAGE 2

FIG-5

FIGURE 1 is a perspective view of my universal joint tester;

FIGURE 2 is a front side elevational view thereof with a portion of the broken line pipe broken away for convenience of illustration;

FIGURE 3 is a back side elevational view thereof;

FIGURE 4 is an end elevational view looking toward the left of FIGURE 2;

FIGURE 5 is an end elevational view looking toward the right of FIGURE 2;

FIGURE 6 is a top plan view thereof; and

FIGURE 7 is a bottom plan view thereof.

The pipe shown in broken lines is for illustrative purposes only.

I claim:
The ornamental design for a universal joint tester, substantially as shown and described.
